US00D939359S

(12) **United States Design Patent** (10) Patent No.: **US D939,359 S**
(45) Date of Patent: **** Dec. 28, 2021**

(54)	PACKAGING FOR A SINGLE DOSE PERSONAL CARE PRODUCT	2,658,072 A	11/1953	Milton
		2,694,668 A	11/1954	Fricke
		2,809,971 A	10/1957	Bernstein et al.
		3,152,046 A	10/1964	Kapral
(71)	Applicant: The Procter & Gamble Company , Cincinnati, OH (US)	3,236,733 A	2/1966	Karsten et al.
		3,321,425 A	5/1967	Blau et al.
		3,332,880 A	7/1967	Kessler et al.
		3,426,440 A	2/1969	Shen et al.
(72)	Inventors: Sharonda Lee Crawford Washington , Cincinnati, OH (US); Marilyn Anne Vennemeyer , Cincinnati, OH (US); William Mercer Benson , Harrison, OH (US); Nicole Alisa Renee Lockett Turner , Fairfield, OH (US)	3,463,308 A	* 8/1969	Deneke B65D 73/0057
		3,489,688 A	1/1970	Pospischil
		3,653,383 A	4/1972	Wise
		3,695,989 A	10/1972	Albert
		3,753,196 A	8/1973	Kurtz et al.
		3,761,418 A	9/1973	Parran
		3,929,678 A	12/1975	Laughlin
		3,967,921 A	7/1976	Haberli et al.
		4,020,156 A	4/1977	Murray et al.
		4,051,081 A	9/1977	Jabs et al.
		4,089,945 A	5/1978	Brinkman et al.
		4,149,551 A	4/1979	Benjamin et al.
		4,196,190 A	4/1980	Gehman et al.
		4,197,865 A	4/1980	Jacquet et al.
		4,206,196 A	6/1980	Davis
		4,217,914 A	8/1980	Jacquet et al.
		4,272,511 A	6/1981	Papantoniu et al.
		4,323,683 A	4/1982	Bolich, Jr. et al.
		4,345,080 A	8/1982	Bolich, Jr.
		D266,829 S	* 11/1982	Yoshizawa D9/415
		4,379,753 A	4/1983	Bolich, Jr.
		4,381,919 A	5/1983	Jacquet et al.
		4,422,853 A	12/1983	Jacquet et al.
		4,470,982 A	9/1984	Winkler
		4,507,280 A	3/1985	Pohl et al.
		4,529,586 A	7/1985	De et al.
		4,536,361 A	8/1985	Torobin
		4,565,647 A	1/1986	Llenado
		D286,450 S	10/1986	Tovey
		4,663,158 A	5/1987	Wolfram et al.
		4,710,374 A	12/1987	Grollier et al.
		4,822,613 A	4/1989	Rodero
		4,885,107 A	12/1989	Wetzel
		4,976,953 A	12/1990	Orr et al.
		4,990,280 A	2/1991	Thorenggaard
		5,055,384 A	10/1991	Kuehnert
		5,061,481 A	10/1991	Suzuki et al.
		5,062,889 A	11/1991	Hoehl et al.
		5,062,994 A	11/1991	Imperatori
		5,094,853 A	3/1992	Hagarty
		5,098,636 A	3/1992	Balk
		5,100,657 A	3/1992	Ansher-jackson et al.
		5,100,658 A	3/1992	Bolich, Jr. et al.
		5,104,646 A	4/1992	Bolich, Jr.
		5,106,609 A	4/1992	Bolich, Jr.

CLAIM

The ornamental design for a packaging for a single dose personal care product, as shown and described.

DESCRIPTION

FIG. 1 is a perspective view of a first embodiment of a packaging for a single dose personal care product, showing our new design;

FIG. 2 is a second perspective view of the packaging of FIG. 1;

FIG. 3 is a front view of the packaging of FIG. 1; FIG. 4 is a first side view of the packaging of FIG. 1; FIG. 5 is a back view of the packaging of FIG. 1; FIG. 6 is a second side view of the packaging of FIG. 1; FIG. 7 is a third side view thereof of the packaging of FIG. 1;

FIG. 8 is a fourth side view of the packaging of FIG. 1; FIG. 9 is a perspective view of a second embodiment of a packaging for a single dose personal care product, showing our new design;

FIG. 10 is a second perspective view of the packaging of FIG. 9;

FIG. 11 is a front view of the packaging of FIG. 9; FIG. 12 is a first side view of the packaging of FIG. 9; FIG. 13 is a back view of the packaging of FIG. 9; FIG. 14 is a second side view of the packaging of FIG. 9; FIG. 15 is a third side view thereof of the packaging of FIG. 9;

FIG. 16 is a fourth side view of the packaging of FIG. 9; FIG. 17 is a perspective view of a third embodiment of a packaging for a single dose personal care product, showing our new design;

FIG. 18 is a second perspective view of the packaging of FIG. 17;

FIG. 19 is a front view of the packaging of FIG. 17;

FIG. 20 is a first side view of the packaging of FIG. 17;

FIG. 21 is a back view of the packaging of FIG. 17;

FIG. 22 is a second side view of the packaging of FIG. 17; FIG. 23 is a third side view thereof of the packaging of FIG. 17;

FIG. 24 is a fourth side view of the packaging of FIG. 17; FIG. 25 is a perspective view of a fourth embodiment of a packaging for a single dose personal care product, showing our new design;

FIG. 26 is a second perspective view of the packaging of FIG. 25;

FIG. 27 is a front view of the packaging of FIG. 25;

FIG. 28 is a first side view of the packaging of FIG. 25;

FIG. 29 is a back view of the packaging of FIG. 25;

FIG. 30 is a second side view of the packaging of FIG. 25; FIG. 31 is a third side view thereof of the packaging of FIG. 25;

FIG. 32 is a fourth side view of the packaging of FIG. 25;

FIG. 33 is a perspective view of a fifth embodiment of a packaging for a single dose personal care product, showing our new design;
FIG. 34 is a second perspective view of the packaging of FIG. 33;
FIG. 35 is a front view of the packaging of FIG. 33;
FIG. 36 is a first side view of the packaging of FIG. 33;
FIG. 37 is a back view of the packaging of FIG. 33;
FIG. 38 is a second side view of the packaging of FIG. 33;
FIG. 39 is a third side view thereof of the packaging of FIG. 33;
FIG. 40 is a fourth side view of the packaging of FIG. 33;
FIG. 41 is a perspective view of a sixth embodiment of a packaging for a single dose personal care product, showing our new design;
FIG. 42 is a second perspective view of the packaging of FIG. 41;
FIG. 43 is a front view of the packaging of FIG. 41;
FIG. 44 is a first side view of the packaging of FIG. 41;
FIG. 45 is a back view of the packaging of FIG. 41;
FIG. 46 is a second side view of the packaging of FIG. 41;
FIG. 47 is a third side view thereof of the packaging of FIG. 41;
FIG. 48 is a fourth side view of the packaging of FIG. 41;
FIG. 49 is a perspective view of a seventh embodiment of a packaging for a single dose personal care product, showing our new design;
FIG. 50 is a second perspective view of the packaging of FIG. 49;
FIG. 51 is a front view of the packaging of FIG. 49;
FIG. 52 is a first side view of the packaging of FIG. 49;
FIG. 53 is a back view of the packaging of FIG. 49;
FIG. 54 is a second side view of the packaging of FIG. 49;
FIG. 55 is a third side view thereof of the packaging of FIG. 49;
FIG. 56 is a fourth side view of the packaging of FIG. 49;
FIG. 57 is a perspective view of an eighth embodiment of a packaging for a single dose personal care product, showing our new design;
FIG. 58 is a second perspective view of the packaging of FIG. 57;
FIG. 59 is a front view of the packaging of FIG. 57;
FIG. 60 is a first side view of the packaging of FIG. 57;
FIG. 61 is a back view of the packaging of FIG. 57;
FIG. 62 is a second side view of the packaging of FIG. 57;
FIG. 63 is a third side view thereof of the packaging of FIG. 57;
FIG. 64 is a fourth side view of the packaging of FIG. 57;
FIG. 65 is a perspective view of a ninth embodiment of a packaging for a single dose personal care product, showing our new design;
FIG. 66 is a second perspective view of the packaging of FIG. 65;
FIG. 67 is a front view of the packaging of FIG. 65;
FIG. 68 is a first side view of the packaging of FIG. 65;
FIG. 69 is a back view of the packaging of FIG. 65;
FIG. 70 is a second side view of the packaging of FIG. 65;

FIG. 71 is a third side view thereof of the packaging of FIG. 65;
FIG. 72 is a fourth side view of the packaging of FIG. 65;
FIG. 73 is a perspective view of a tenth embodiment of a packaging for a single dose personal care product, showing our new design;
FIG. 74 is a second perspective view of the packaging of FIG. 73;
FIG. 75 is a front view of the packaging of FIG. 73;
FIG. 76 is a first side view of the packaging of FIG. 73;
FIG. 77 is a back view of the packaging of FIG. 73;
FIG. 78 is a second side view of the packaging of FIG. 73;
FIG. 79 is a third side view thereof of the packaging of FIG. 73;
FIG. 80 is a fourth side view of the packaging of FIG. 73;
FIG. 81 is a perspective view of an eleventh embodiment of a packaging for a single dose personal care product, showing our new design;
FIG. 82 is a second perspective view of the packaging of FIG. 81;
FIG. 83 is a front view of the packaging of FIG. 81;
FIG. 84 is a first side view of the packaging of FIG. 81;
FIG. 85 is a back view of the packaging of FIG. 81;
FIG. 86 is a second side view of the packaging of FIG. 81;
FIG. 87 is a third side view thereof of the packaging of FIG. 81;
FIG. 88 is a fourth side view of the packaging of FIG. 81;
FIG. 89 is a perspective view of a twelfth embodiment of a packaging for a single dose personal care product, showing our new design;
FIG. 90 is a second perspective view of the packaging of FIG. 89;
FIG. 91 is a front view of the packaging of FIG. 89;
FIG. 92 is a first side view of the packaging of FIG. 89;
FIG. 93 is a back view of the packaging of FIG. 89;
FIG. 94 is a second side view of the packaging of FIG. 89;
FIG. 95 is a third side view thereof of the packaging of FIG. 89;
FIG. 96 is a fourth side view of the packaging of FIG. 89;
FIG. 97 is a perspective view of a thirteenth embodiment of a packaging for a single dose personal care product, showing our new design;
FIG. 98 is a second perspective view of the packaging of FIG. 97;
FIG. 99 is a front view of the packaging of FIG. 97;
FIG. 100 is a first side view of the packaging of FIG. 97;
FIG. 101 is a back view of the packaging of FIG. 97;
FIG. 102 is a second side view of the packaging of FIG. 97;
FIG. 103 is a third side view of the packaging of FIG. 97; and,
FIG. 104 is a fourth side view of the packaging of FIG. 97. The evenly spaced broken lines are shown for the purpose of illustrating parts of the article that form no part of the claim. The dash-dot broken lines illustrate a boundary to the claim and form no part thereof.
